UNITED STATES PATENT OFFICE.

WILLIAM P. PHILLIPS, OF BOSTON, MASSACHUSETTS.

OIL-CUP LUBRICATOR.

No. 872,012.

Specification of Letters Patent.

Patented Nov. 26, 1907.

Application filed February 6, 1907. Serial No. 356,023.

To all whom it may concern:

Be it known that I, WILLIAM P. PHILLIPS, a citizen of the United States, and a resident of Boston, in the county of Suffolk and State 5 of Massachusetts, have invented an Improvement in Oil-Cup Lubricators, of which the following description, in connection with the accompanying drawings, is a specification, like letters on the drawings representing 10 like parts.

This invention relates to oil cup lubricators whereby oil or similar lubricating medium may be fed to the desired portions of mechanisms of various types.

15 While the invention is particularly useful in connection with gas engines or explosive engines of various types, it is in certain of its features applicable to many other types of engines or mechanisms and may with regard 20 to such features be of general application.

The invention more particularly relates to the provision of means whereby the valve and its related parts and herein the main cover and filling cover may be held in proper 25 position.

In order that the principles of the invention may be fully understood, I have shown a single type or embodiment of the invention in the accompanying drawing, wherein

30 Figure 1 is a side elevation of a lubricator embodying my invention, the valve being seated; Fig. 2 is a vertical central section of the lubricator, upon an enlarged scale, the valve being lifted from its seat; Fig. 3 is a 35 side elevation of the valve and parts directly carried thereby; and Fig. 4 is a detail sectional view showing the main cover open.

Referring to the single type or embodiment of the invention disclosed in the accompanying drawing, the lubricator cup is indicated at 1, it preferably and as here shown being of transparent material.

The cup is adapted to be mounted in any suitable manner upon the mechanism to be 45 lubricated, which may be a gas or explosive engine or other mechanism.

As here shown a valve seat 2 is formed upon the lower portion of a vertically disposed valve casing 3 extending through the 50 cup and the cover thereof, the lower end of the casing being preferably screw threaded to receive a fitting 4 whereby the lubricator may be secured to the mechanism to be lubricated, such fitting preferably having the 55 usual or any desired sights.

Mounted within the valve casing is a ver-

tically disposed valve 5 adapted to be seated against the valve seat 2 and to extend longitudinally of and beyond the upper end of the valve casing 3.

In the present form of the invention, a main cover 6 is provided which may have a flange concentric with and preferably surrounding the upper edge of the cup. Such cover is here shown as having an opening 7 60 therein, preferably concentric with and surrounding the valve casing. Mounted upon such cover and of slightly larger diameter than the opening 7 is a supplemental or filling cover 8, preferably formed as a thin metallic disk, such cover being mounted upon the valve casing and preferably so tightly fitting the same as to have little or no longitudinal movement thereon. If desired, and as indicated in Figs. 1 and 2, the supplemental 65 cover may comprise an upper and a lower portion. The lower portion 8' may be non-metallic and tightly fit the valve casing, the upper portion being preferably metallic and resting thereon, and if desired loosely fitting 70 the valve casing.

The valve 5 has loosely mounted thereon a cap or memer 9, a depending cylindrical portion thereof which is preferably employed being here shown as interiorly screw threaded to engage exterior threads upon the upper end of the valve casing. The valve 5 has fixed thereon a collar 10 between which and the inner face of the top of the cap 9 is disposed a spiral spring 11. When the cap 9 is 85 secured upon the upper edge of the valve casing, the tension of the spring 11 is thereby increased, the valve being thus forced to its seat and maintained there by such spring pressure. In order to lift the valve from its 90 seat without unscrewing the cap 9, preferably a pivoted cam lever 12 is pivoted to the valve 5 at or near its upper end. When the cam lever is turned into a horizontal position as indicated in Fig. 1, the valve is pressed to 95 its seat by the spring 11, but when the lever is turned into an upright position as indicated in Figs. 2 and 3 the engagement of the foot of the lever 12 upon the upper face of the top of the cap 9 elevates the pivot of said 100 lever, and hence lifts the valve from its seat.

In a lubricator valve as thus far described, when the valve is seated, that is, when the cam lever is removed from engagement with the upper face of the top of the cap 9, the 110 cap 9 is maintained in its adjusted or correct position by means of the pressure of the

spring 11 against the under face of the top of the cap 9, and the friction between such cap and the spring is sufficient to prevent rotation of the cap excepting as considerable and 5 intentional force is applied thereto and hence the parts are maintained in correct position. When, however, the valve is elevated from its seat by the described engagement of the cam lever 12 with the cap, then 10 such lever, the valve 5 upon which it is mounted, the spring 11 and the cap 9 become as it were locked together and act as an entirety and hence there is nothing to prevent rotation of the cap 9 upon the screw 15 threads at the upper edge of the valve casing for the friction between the cap and the spring 11 is neutralized by the engagement of the lever 12 and the cap. Thus the adjustment of the cap 9 may be accidentally 20 changed.

Devices have heretofore been employed to engage with a cap or other part upon a valve to prevent rotation thereof, said devices sometimes assuming the form of a bowed 25 spring clip, a portion whereof engages the roughened face of the cap.

In accordance with my invention, I employ a spring which holds the cap 9 from rotation whether the valve 5 be seated or not, 30 and, in the present type of the invention, such spring performs the further function of holding the supplemental or filling cover in position and holding the main cover 6 in place. In the present type of the invention, 35 such spring is indicated at 13, it being preferably a coil spring surrounding the valve casing and engaging at its lower end the upper face of the supplemental cover and at its upper end a portion of the cap 9 and herein 40 its lower edge, thus exerting its tension against both of said parts and preventing rotation of the cap 9 upon the valve casing, whether the valve be seated or unseated.

In order to fill the lubricator cup, in the 45 present type of the invention, the main cover 6 is slightly lifted at one portion of its edge, so that its flange is brought above the upper edge of the cup and then is slid laterally beneath the supplemental cover 8 until 50 a portion of the concentric opening 7 in the main cover is exposed. After filling the cup, the main cover is returned by a reverse operation.

It will be observed that in the present type 55 of the invention, the spring 13 performs the triple function of preventing rotation of the cap 9 and of holding the supplemental cover 8 and the main cover 6 in position.

Having thus described one type or embodiment of the invention, I desire it to be understood that although I have used specific terms, they are employed in a descriptive and generic sense and not for purposes of limitation, the scope of the invention being 60 set forth in the following claims.

1. A lubricator having a valve spring-pressed to its seat, said valve having a cap thereon, a valve casing, a screw threaded connection between said cap and the valve casing, means engaging said cap to lift the valve 70 from its seat, a cover for the lubricator and a coiled spring interposed between and bearing against the cover and the cap.

2. A lubricator having a valve spring-pressed to its seat, a cap upon said valve 75 internally screw threaded, a valve casing having an exterior screw threaded upper end, means mounted upon said valve and engaging said cap to lift the valve from its seat, a cover for the lubricator and a coiled spring 80 interposed between and bearing against said cap and said cover.

3. A lubricator having a valve 5, a coiled spring 11 to press the same to its seat, a cap 9 upon said valve, a valve casing 3, said cap 85 and valve casing having a screw threaded engagement, a cam lever 12 mounted upon said valve, a cover 6 upon the lubricator, and a coiled spring 13 between and engaging with said cover and said cap. 90

4. A lubricator having a valve provided with a fixed shoulder, a member longitudinally and rotatably movable upon said valve, a coiled spring interposed between said shoulder and said member, a fixed part of the lubricator wherewith said member has an engaging connection, means upon the valve to lift the same from its seat, a cover for the lubricator, and a coiled spring surrounding 95 said valve and engaging said cover and said member to maintain them in position. 100

5. A lubricator having a main cover provided with a filling opening concentrically formed therein, and a supplemental cover for such opening, said covers having relatively lateral movement. 105

6. A lubricator having a main cover provided with a filling opening concentrically formed therein and a valve and valve casing extending through such opening in the cover, 110 and a supplemental cover for such opening, said cover and supplemental cover having relative, lateral, bodily movement upon the lubricator, to close and unclose the opening.

7. A lubricator having a main cover and a 115 spring to hold the same to its seat, said cover being mounted for lateral movement with respect to the lubricator body, said cover having a filling opening therein permitting filling of the lubricator through the cover. 120

8. A lubricator having a main cover, a supplemental or filling cover mounted thereon, and a common means to hold the same in position, but permitting relative movement of said covers. 125

9. A lubricator having a main cover with a concentrically disposed filling opening, and a supplemental cover for such filling opening, said supplemental cover being of a disk like formation. 130

10. A lubricator having a main cover with a concentrically disposed filling opening and a supplemental cover for such filling opening, such covers being in frictional engagement 5 only and mounted for relative, bodily movement to close and unclose the filling opening.
11. A lubricator having a valve casing, a main cover and a supplemental or filling cover mounted upon said valve casing, said 10 covers having capacity for relative, bodily, lateral movement.
12. A lubricator having a valve casing, a main cover having a concentric filling opening therein and a supplemental or filling 15 cover mounted upon said main cover and closing said filling opening therein and mounted for relative, bodily movement to close and unclose the filling opening.
13. A lubricator having a main cover provided with an opening therethrough, a valve casing passing through said main cover, a supplemental or filling cover overlying the opening in the main cover and a spring engaging the upper face of said supplemental 25 cover to maintain it in position.
14. A lubricator, having a valve casing, a main cover for the lubricator having an opening therein surrounding said valve casing and of a diameter to permit lateral movement of said cover, and a supplemental 30 cover overlying the opening in said main cover.
15. A lubricator having a main and supplemental cover, said main cover having a filling opening therein and having capacity 35 of lateral movement upon the lubricator with respect to the supplemental cover, thereby to expose the filling opening in the main cover, and yielding means holding said 40 covers in position but permitting such relative, lateral movement.
16. A lubricator having a main and supplemental cover, said main cover having a filling opening therein adapted to be closed 45 by said supplemental cover, said main and supplemental covers being mounted for relative bodily lateral movement, whereby the filling opening in the main cover may be exposed and yielding means holding said covers 50 in position but permitting such relative, lateral movement.
17. A lubricator having a main cover with an opening therein, a supplemental or filling cover for such opening, a valve adapted to be 55 spring pressed to its seat, a member upon said valve, a fixed part of the lubricator wherewith said member engages, and a common means engaging said member and said 60 supplemental or filling cover to maintain in position said member, said main cover and said supplemental cover.
18. A lubricator comprising a cup 1, a valve casing 3, a valve 5 mounted therein, a spring 11 to press the same to its seat, a cap 9 upon the valve having locking engagement 65 with the casing, a main cover 6 having an opening 7, supplemental or filling cover 8, and a coiled spring 13 surrounding said valve casing and bearing against said cap 9 and said supplemental cover 8 to maintain 70 said cap, cover and supplemental cover in position.
19. A lubricator having a valve spring pressed to its seat, a member mounted upon the valve and longitudinally and rotatably 75 movable with respect thereto, said member detachably engaging a fixed part of the lubricator, and a plurality of springs engaging the lower face of said member to prevent undue rotation thereof. 80
20. A lubricator having a valve casing, a member attached thereto, a main cover having an opening therein, a supplemental or filling cover for such opening, and a common means engaging said member and said supplemental or filling cover to maintain in position said member, said main cover and said supplemental cover. 85
21. A lubricator having a valve casing, a member attached thereto but capable of movement relative thereto, said member co-operating to lift a valve of the lubricator, a main cover having an opening therein, a supplemental or filling cover for such opening, and a common means engaging said member 90 and said supplemental or filling cover to maintain in position said member, said main cover and said supplemental cover. 95
22. A lubricator having a main cover with a filling opening therein and a supplemental cover for such filling opening, such covers being in frictional engagement only and mounted for relative, bodily movement to close and unclose the filling opening. 100
23. A lubricator having a valve provided with a fixed shoulder, a member longitudinally and rotatably movable upon said valve, a spring interposed between said shoulder and said member, a fixed part of the lubricator wherewith said member has an engaging connection, means upon the valve 105 to lift the same from its seat, a cover for the lubricator and a spring encompassing said valve and engaging said cover and said member to maintain them in position. 110
- In testimony whereof, I have signed my name to this specification, in the presence of two subscribing witnesses.
